FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged view of portion 9 shown in FIG. 1;

FIG. 10 is an enlarged view of portion 10 shown in FIG. 2;

FIG. 11 is another front, right, and top perspective view thereof, shown with an additional environmental subject matter; and,

FIG. 12 is another front, right, and top perspective view thereof, shown in an alternate configuration.

The dash-dash broken lines in the drawings depict portions of the smart watch band with protective case that form no part of the claimed design. Additional dash-dash broken lines shown in FIGS. 11 and 12 depict an environmental subject matter and form no part of the claimed design. The dot-dash broken lines shown in FIGS. 1, 2, 9, and 10 represent boundaries of the enlarged portions and form no part of the claimed design.
